(57) **CLAIM**

The ornamental design for a fuse cover, as shown and described.

DESCRIPTION

FIG. 1 is a perspective view of a fuse cover of my new design, with the fuse cover shown in a closed position; FIG. 2 is a front elevational view of the fuse cover of FIG. 1;

FIG. 3 is a rear elevational view of the fuse cover of FIG. 1; FIG. 4 is a left side plan view of the fuse cover of FIG. 1; FIG. 5 is a right side plan view of the fuse cover of FIG. 1; FIG. 6 is a top plan view of the fuse cover of FIG. 1; FIG. 7 is a bottom plan view of the fuse cover of FIG. 1; FIG. 8 is a sectional view of the fuse cover of FIG. 1, taken at line 8-8 of FIG. 6;

FIG. 9 is a sectional view of the fuse cover of FIG. 1, taken at line 9-9 of FIG. 6;

FIG. 10 is a sectional view of the fuse cover of FIG. 1, taken at line 10-10 of FIG. 2;

FIG. 11 is a sectional view of the fuse cover of FIG. 1, taken at line 11-11 of FIG. 2; and,

FIG. 12 is a perspective view of the fuse cover of FIG. 1, with the fuse cover shown in an open position.

The Dash-Dash-Dash broken lines represent portions of the of the fuse cover that form no part of the claimed design. The Dash-Dot broken lines in FIGS. 2 and 6 depict the boundaries of the cross sections that form no part of the claimed design.

1 Claim, 7 Drawing Sheets
